UNITED STATES PATENT OFFICE.

NATHANIEL O. GOLDSMITH, OF NORWOOD, OHIO, ASSIGNOR TO THE WEIR FROG COMPANY, OF NORWOOD, OHIO, A CORPORATION OF OHIO.

MULTIPLE DRILL.

1,249,379.

Specification of Letters Patent. Patented Dec. 11, 1917.

Application filed March 19, 1917. Serial No. 155,678.

To all whom it may concern:

Be it known that I, NATHANIEL O. GOLDSMITH, a citizen of the United States, and a resident of Norwood, in the county of 5 Hamilton and State of Ohio, have invented certain new and useful Improvements in Multiple Drills, of which the following is a full, clear, and exact description, reference being had to the accompanying drawings, 10 forming part of this specification.

My invention relates to multiple drills particularly of the type adapted for drilling holes in steel rails for railroad use. It is requisite in drills of this type to drill holes 15 quite close together and accurately placed in the rail webs, and these holes are to be drilled all at one operation.

In United States Patent No. 378,748, dated February 28, 1888, issued to Weir, 20 Partington and Goldsmith, is shown and described a multiple drill for a like purpose, and in this drill as in the invention herein, there are adjustable heads, one for each drill, which slide longitudinally of the machine, 25 and in which the operating parts for adjacent drill heads are set alternately high and low so that the heads may be brought close together for drilling holes in rails, without the operating parts interfering with 30 each other.

The object of my invention is to provide means whereby a number of holes can be drilled in material, these holes spaced at different distances apart in planes either parallel or intersecting. Also means whereby the 35 material can be mechanically carried under the drill heads and adjustably located in proper position, which can be held in proper position while the drilling operation is performed, and mechanically carried away from 40 the drill heads after the drilling is done, with means for mechanically supplying lubricant to the drills, carrying away said lubricant and cleaning the machine of the 45 resulting chips.

I accomplish this by a machine having a bed plate, two or more housings which support a cross rail upon which are carried a number of sliding drill heads adjustable 50 along said rails and also adjustable in a plane at right angles with said rail. The said bed plate also supports a power moving table, with a means for reversing direction of its movement, and is provided with suitable power driven rollers, with clamping 55

and adjusting devices, with adjustable and rotating stops. The said table is skeleton frame with deflecting aprons to carry lubricant and chips away from the supports upon which the material rests while the drilling 60 operation is performed.

This feature of a skeleton framework in itself forms a valuable and important part of the invention, and while other features of the invention relate specifically to improvements in multiple drills, it will be understood that the skeleton framework construction is applicable to many other machines such as milling machines, boring machines, planers and the like where quick 70 elimination of the lubricant and the chips is important.

The drawings show conical rollers (17), a shape especially designed to support and carry a railroad T rail, but I do not wish 75 to limit myself to this conical shape, as it can readily be seen that the shape of the rollers can be changed to accommodate any section, either flat, round, I beam or any other form which the material to be drilled may have, or the rollers may support a drilling jig which holds a number of separate pieces, 80 each of which is to be drilled independently.

The above objects and purposes I accomplish by that certain construction and arrangement of parts to be hereinafter more 85 specifically pointed out and claimed.

In the drawings,

Figure 1 is a vertical section of the machine on the line 1, 1, of Fig. 2, showing 90 a drill head in vertical section.

Fig. 2 is a front elevation of the machine.

Figs. 3 and 4 are side elevations of the two parts of a drill head, disassembled.

Fig. 5 is a detail top plan view of the 95 table showing one of the machine standards in section.

Fig. 6 is a detail section of the head revolving means.

100

The bed and table.

The entire machine is supported on a bed 1, which has several standards 2 extending up therefrom. The work supporting table 3 is mounted so as to slide upwardly and 105 downwardly on the side standards (Fig. 5) by means of stout plates 4 which are bolted onto extensions 5 mounted along the back of the table. These extensions overlap the flanges 6, 6, on the forward side of the 110

standards. As shown, the standards are hollow for purposes of lightness and economy, and this renders somewhat confusing the showing in Fig. 1, but it will be readily understood that any desired means for providing a sliding support for the table on the standards will be sufficient.

In the base of the table at the desired number of points along the same, are thrust 10 bearings 7, in which are mounted and keyed against rotation the large screws or captans 8. Under these bearings, for receiving the screws in the bed of the machine, are individual casings for each screw device, 15 said casings having the top members or plates 9 and the base plates 10, said base plates having sleeves 11, which seat in suitable holes in the bed.

Inside of the casings and threaded so as 20 to engage the screws, are worm wheels 12 having sleeve portions or hubs 13, which are the threaded parts of the wheels and which engage around the screws. Running along the front of the machine and suitably 25 supported in cylindrical casings 14 that bolt to the front of the screw and worm wheel casings, is a shaft 15. This shaft carries, inside of said cylindrical casings, worms 16 that mesh with the worm wheels 12. The 30 revolving of the shaft causes the worm wheels to turn, and since the screws or captans are held nonrotatably in the table, the sleeves or hubs of the worm wheels will cause the table to rise or fall as desired. No 35 particular form of drive for the device is shown, but it will be understood that when revolving the shaft 15 is provided which will cause the table to rise slowly carrying the 40 work up against the drills, and when the drilling is completed to stop the revolution and reverse it for bringing the table back to its original position.

Mounted along the table at a number of 45 points are the conical rollers 17, the same having supporting journals at 18 and 19 in members 20 and 21, extending the length of the table and forming part of the skeleton frame. While we have described the 50 part 3 as a table, the present machine differs quite materially from ordinary drilling machines in that there is no table in the true sense. The part marked 3 forms a rear or inner portion of a skeleton framework and 55 the members 20 the front portion of this skeleton framework, while the rollers 17 support the work to be operated on. Thus the table so to speak is a support for the work, open between the front and rear portions, with transverse supporting rollers to 60 support the work. Thus there is no table to collect chips and cuttings from the drills, but these cuttings at once drop down between the rollers. These rollers are mechanically driven, as will be described, and are

the support for the rails 22. Since they are conical, the rails will lie along their surface so as to support the webs in horizontal position while being drilled, but if other shapes of rails or I-beams or channel bars are to be 70 accommodated by the machine, then other shaped rollers should be used. There are two clamping bars which run the length of the table, the outer bar being the movable bar and the inner bar being adjustable. The 75 provision of adjustability of the inner bar in coöperation with the conical support, permits the exact positioning of the rails of different heights. The whole table may be made in one skeleton casting, with spaces 80 for the rollers opening below into the oil aprons or troughs to be hereinafter described.

Operated from a splined shaft 17^a, operated from the drill operating gears, is a gear 17^b at the right end of the table. Supported along the front of the table is the shaft 17^c, which by means of gears 17^d drives the rail supporting rollers, the roller shafts 18 having each a gear 18^a meshing with the shaft 90 driven gears 17^d.

The inner bar 23 of the rail clamping device has spaced along the top thereof a number of housings 24 for a shaft 25 that extends the length of the machine. The bar 95 is cut away beneath the housings 24 so as to receive a worm wheel 26, and this worm is mounted and splined on a screw 27. The screws 27 are journaled in the bar and extend rearwardly therefrom where they enter a threaded socket 28 in the standard 2.

Mounted on the shaft 25 inside of the housings is a worm 26^a which meshes with the worm wheels 26. By revolving the shaft 25 by hand, in some such way as fitting a 105 wrench over its end, or the like, the worm wheels and the screws will act so as to force the bar 23 forward or back as desired. The screws and worms turn together, and the screws feed in and out of the sockets in the 110 main standards.

The front clamp bar 29 is made of heavy iron, to which is secured a socket member 31. A bolt 32 in the socket piece serves to retain the thrust bar 33 of the device for 115 advancing the clamping plate. A lever 34 pivoted at 35 to the table and pivoted to the thrust bar is connected at its lower end to the piston rod 36 of an air cylinder 37. This cylinder may be of any type and suitably mounted on the table. It is shown in Fig. 1 only diagrammatically.

In mounting a rail on the table, it is fed to the conical rollers with the head of the rail toward the front of the machine or to 125 the base of the rollers. The revolving rollers will draw the rail quickly into place and bring it up against one of the stops to be described. The air is then turned on in the front clamp device and the bar thereof will 130

be advanced against the head of the rail, clamping it in place. To eject the rail, it is understood that the rollers again will move it out quickly and easily, the whole 5 table moving up and back during each drilling.

It should be noted that mounted in the inner ends of the arms or thrust bars of the forward clamp is a rod 38 which runs the 10 length of the machine and may be used to push in the clamp bar at points where there is no separate device provided for the purpose.

The raising of the table has been described, 15 and it can be seen that by doing so the rail properly centered and clamped tightly can be brought up against a large number of drills for simultaneously boring or drilling holes in the web thereof.

20

The drill heads.

The drill heads are stationary so far as up and down movement is concerned, and separately adjustable along the machine 25 longitudinally, as well as movable in the arc of a circle so as to provide for different alignments for the different heads or drilling units.

The heads are all of the same height, but 30 are adapted to drive alternately from two shafts one above the other. Also the driving gears for the drills are arranged alternately one up and one down on the frames of the heads.

35 As shown in Figs. 3 and 4 (which show one of the upper driven and upper geared heads) there is in each instance a standard 40 for each head, this standard serving to mount the gears 41 and 42 which are coupled together. Below the standard portion 40 is the main piece 46 of the heads. This main piece has guide plates 47 and 48 mounted at the rear thereof, and adapted to engage over the extending flanges 49 of the 45 horizontal frame piece 50.

This piece 50 is suitably mounted on the standards 2 of the main frame, and has along 50 its lower portion a rack 51 by means of which the longitudinal adjustment of the heads is accomplished. At the lower end of the main frame portion of the heads is a hole for a stub shaft 52 which carries a pinion 53, said pinion being located in a suitable recess in the said head frame portion and 55 being in mesh with the rack above mentioned. By turning the stub shaft 52 by means of its head 55, the drill frame can be adjusted along the horizontal frame piece 50 of the machine.

60 It should be understood that the above described members of the drill head frame, *i. e.* the standard portion and the main portion that slides longitudinally of the machine, are preferably in one piece.

65 To the standard portion at the rear is

bolted a yoke member 56 or 56^a, the former being for the upper drive and the latter for the lower. The only difference is in the shape of the yoke members, or rather the arrangement of the yoke members on the 70 standard since they are duplicates of each other and simply alternately reversed. The yoke members at the narrow portion thereof are provided with bearings 57, which rotatably carry beveled gears 58. Dependent 75 upon whether the gears 58 are high or low, they are mounted on one of the shafts 59, 60. The gears 58 are splined to the shafts so as to slide thereon but rotate therewith, and said gears are carried in the bearings of 80 the yokes. Thus at whatever position the yokes are set along the machine the gears 58 will be driven. These gears mesh with the gears 41 held at the rear of the standards and drive the gears 42. Thus either 85 the upper or lower shaft will drive the drill operating gears no matter where along the machine the drill head is located.

The cylindrical members 61 which contain the drill shaft 62 have bosses 61^a that 90 extend over the forward projection of the main frame portion of the heads. In the showing in Fig. 3, the upper boss 61^a on alternate cylindrical members for operation from the upper shaft is quite high, which is not 95 the case in the lower operated drills. It is required to have this to give support to the drill driving gears which must be high to meet the gears driven from the yokes and the said upper shaft.

A shaft 63 passes down through the bosses and the main frame portion and carries at its upper end the gear and beveled pinions 64, 65, the former of which meshes with the gear 66 on the drill shaft. The pinion 65 meshes with the gear 42 in the standard 105 portions of the drill frames. Thus the drive from the two cross shafts of the machine, be the same the higher or the lower shaft, will be communicated by the various gears 110 above described to the drill shaft.

The purpose of the arrangement of the cylindrical members which carry the drill shafts is so that they will be revolvable on the main frame portion of the drill heads. 115 It can be seen that the shaft 63 serves as the pintle of a hinge on which the drill shaft retaining members will swing on the balance of the frame.

This swinging can be done without bringing the driving gears out of mesh as the gear 66 travels around on the center of the gear 64. Set in the boss 61^a at the lower end of the cylindrical drill shaft retaining member of each drill head, is a sleeve 67 that 120 is keyed at 68 to the inside of the boss. This sleeve only loosely engages over the shaft 63 which passes through the boss, and at the lower end of the sleeve is a worm wheel 125 70. Mounted horizontally in the lower end 130

of the main frame portion of the heads is the worm 71 (Fig. 6) which is turned by means of its square end 72. The revolving of this worm which is in mesh with the 5 worm wheel last above described, will cause the cylindrical member to revolve around on the shaft 63 as a hinge pintle, thereby swinging the drill shaft into any desired position over the work out of alinement 10 with the other drills.

A series of lubrication supply pipes 73 are provided discharging directly over the work as nearly as possible. A large quantity 15 of lubricant may be used without excessive waste, because of the fact that it is caught and returned by means of trough members 74 formed as part of the table casting beneath the recesses therein for the conical rollers. At the front of the table 20 and the lower end of the troughs are aprons 75 suitably bolted in place.

These aprons permit all of the lubricant falling on the work to run down into the trough 76 formed at the front of the machine base. From this point the liquid can be easily strained and pumped back for further use. The pouring of lubricant on in this way results in the carrying away of chips and the like cut out in drilling and 30 makes the work easy and not destructive to the drills, or other cutting tools.

It is believed that the various features of the machine have now been pointed out and their operation described. The operations 35 are generally the same for a certain number of rails, and thus when the adjustable parts are set, the machine can be used to rapidly drill the required holes. This adjustment will be to set the drill heads at the proper 40 relative position to each other longitudinal of the machine, and also set them with regard to the alinement of the drills along the webs of the rails. Extending along the machine between supports 90, 90, is a marked 45 bar or scale 91. Each of the drill heads has a forwardly extending lug 92 which rides under the bar and thereby the drilling points can be accurately measured. The rear clamping member is to be adjusted for the height 50 of rail that is to be used, it being understood that the air operated clamp will always advance to about the same position over the table.

When these various adjustments are made 55 the rails may be slid into the machine, one after another drilled at one operation and rolled on out. There is no need of describing the means of driving the drill operating shafts or the table raising worms. These 60 may be of any type desired.

The yoke members are formed of the same shape, so that they may be used interchangeably, notwithstanding the staggered arrangement of the heads, by simply reversing 65 the position of the yoke. As many of

the heads may be used as desired and the rest removed from the machine.

For a stop for the positioning rail sections in the machine, a rod 80 is journaled in brackets 81 along the machine, said 70 brackets being mounted on the standard members at the front of the table which are not used as a support for the clamp air cylinders. On the rod 80, pivotally mounted by their journals 83, are hooked stop 75 members 82, shaped like the numeral 7, which are adapted to swing down separately with their ends in the space between the two clamping members of the table. Collars 84, slideable along the rod on each side of the 80 journals 83 provided with set screws, serve to position the stops adjustably. When in use they are tipped down by means of handles 85, so that the ends of the hooks lie in the space over the rollers. These stop 85 members are used to be projected into the pathway of the rail which is to be drilled so as to form an abutment or stop and thus fix the position of the rail under the drills. For example, a number of rails may be, say, 90 ten feet long, others five feet, others twenty feet and so forth. These stops are located at the right position and when the five-foot stops are being entered under the drills, the proper stop is thrown down for that 95 length of rail, and thus the drills will all come at exactly the same place on such length. Another length of rail being entered, the first stop is thrown up out of the way and the second one thrown down. 100 These stops are all arranged for the various lengths, so that no time need be taken in adjusting the metal to be drilled into proper position.

The details of the machine may be modified by the substitution of equivalent structures without departing from the spirit of my invention, and I do not wish the failure to mention such structures in the above matter to give a narrower construction to the 110 claims that follow than their wording would ordinarily imply.

Having thus described my invention, what I claim as new and desire to secure by Letters Patent, is:—

115

1. In a machine of the character specified, a revolving cutter, means for supplying lubricant to the cutting portion thereof, a supporting table of skeleton form, with work supporting rollers thereon spaced apart 120 to form passageways for the lubricant and chips.

2. In a machine of the character specified, a revolving cutter, means for supplying lubricant to the cutting portion thereof, a supporting table of skeleton form, with work supports thereon spaced apart to form passageways for the lubricant and chips, and a deflecting apron to carry off the lubricant and chips.

130

3. In a machine of the character specified, a revolving cutter, means for supplying lubricant to the cutting portion thereof, a supporting table of skeleton form, with 5 work supports thereon spaced apart to form passageways for the lubricant and chips, and a deflecting apron to carry off the lubricant and chips, with a receiving reservoir for the lubricant and chips.
- 10 4. In a machine of the character specified, a work supporting table of skeleton form, a clamping device therefor, and independent work supports spaced apart to form passageways for the lubricant and chips, said 15 supports being placed transverse and below the jaws of said clamping device.
5. In a machine of the character specified, a work supporting table of skeleton form, a clamping device therefor, and independent 20 work supports spaced apart to form passageways for the lubricant and chips, said supports being placed transverse and below the jaws of said clamping device, in combination with means for moving said table.
- 25 6. In a machine of the character specified, one or more slidably adjustable cutting heads, each consisting of a body and a hinged member, which rotates on an axis at right angles to the travel of the body, in combination with the worm and wheel for 30 adjusting and holding said hinged member in fixed position with relation to the body.
7. In a multiple drill, the combination with a pair of driving shafts, a series of 35 drill heads adapted to be mounted in desired position in the machine, members forming part of said heads and lying adjacent to said shafts alternately for each head, and yokes on the said members, said yokes having journals therein for supporting a driving member over one of said shafts, said yokes being interchangeable to bring the journals therein high and low with relation to the heads so as to alternately drive the 40 heads from the upper and lower shafts.
8. In a machine of the character specified, a revolving cutter, means for supplying lubricant to the cutting portion thereof, a table, with a plurality of supports for the work, with passageways through the table 50 and between the supports for the lubricant and chips.

NATHANIEL O. GOLDSMITH.
